UNITED STATES PATENT OFFICE.

THOMAS H. WILKINSON, OF CRANFORD, NEW JERSEY, ASSIGNOR TO GUSTAV H. FROMMANN, OF CONCORD, NEW YORK.

DISPLAY DEVICE.

Application filed March 2, 1926. Serial No. 91,656.

My invention relates to devices for displaying merchandise, advertisements and other articles, and the same has for its object more particularly to provide a simple, 5 efficient and reliable device which may be readily produced from a single blank of suitable material, such as card-board or the like, and which may be readily adjusted to position to serve as a support for displaying 10 articles of merchandise or the like upon counters, show-cases or in windows.

Further, said invention has for its object to provide a device of the character specified which in its knocked-down or normal 15 state for shipment may be folded to render the same compact for transportation and storage purposes, in connection with the articles eventually to be displayed thereon, and which may be readily folded or adjusted 20 to operative position to support the articles to be displayed thereon.

Further, said invention has for its object to provide a foldable support consisting of a 25 pair of end members or wings, and intermediate connected members forming a forwardly-extending inclined support to receive and retain thereon the article to be displayed.

Further, said invention has for its object 30 to provide a device of the character specified which is partly held in adjusted or operative position by the article supported thereby.

Further, said invention has for its object 35 to provide a device of the character specified which when adjusted to operative position will be firm and rigid and capable of supporting the article to be displayed thereon in exposed position without danger of becoming overbalanced and tipping over.

Other objects will in part be obvious and in part be pointed out hereinafter.

To the attainment of the aforesaid objects and ends, my invention consists in the novel 45 details of construction and in the combination, connection and arrangement of parts hereinafter more fully described and then pointed out in the claims.

In the accompanying drawings showing 50 an illustrative embodiment of the invention,

Figure 1 is a face view, with parts extended, showing one form of device constructed according to and embodying my said invention;

Fig. 2 is a front view of the stand or support as set up;

Fig. 3 is a perspective thereof, illustrating how an article is supported thereby;

Fig. 4 is a top view of Fig. 3, and

Fig. 5 is a view similar to Fig. 2, showing means for holding the wings or lateral portions of the device secured together.

Referring to Figure 1 of the drawing, the device is preferably formed from a blank of material 10, such as card board or the like, 65 which is weakened or scored along three vertical parallel lines 11, 12 and 13, to provide lateral portions or wings 14 and intermediate connected portions 15.

The intermediate portions 15 are of reduced height compared to the height of the wings 14. The upper edges 16 of said portions 15 converge downwardly from the intermediate points 17 on the lateral portions 14 to the points 18 near the center line 13, and then converge upwardly at right angles to the downwardly converging edge portions to form a projection 19. The lower edge 20 of said blank 10 is preferably straight.

At Figs. 2, 3 and 4, the blank or device 80 10 is shown adjusted to position to support an article to be displayed which is indicated at A. As shown the intermediate portions 15 are folded towards each other along the line 13 to form a forwardly projecting angular or V-shaped support, indicated at 21, while the lateral portions or wings 14 are folded forwardly along the lines 11 and 12 to form lateral extensions. When the blank is folded as shown, the lower edge 20 serves to properly support the device upon a flat surface.

The article A is received in the recesses or notches formed in the upper parts of the intermediate portions 15, and the same is retained in position thereon between the 95 projection 19 and the lateral portions or wings 14. With the article supported as illustrated, the center of gravity thereof is disposed within the confines of the base 20, so that said device will support the article 100 without danger of toppling over. Further, the article, since the same bridges or straddles the portions 15, serves to prevent said device from spreading out laterally. If preferred, as shown at Fig. 5, additional 105 means 22, such as a string, rubber, strip of card board, or the like may be inserted in the slots 23 of the wings 14 to hold the

wings together and the device as a whole against spreading apart.

The article A is carried by the forward portion of the device in exposed position.

5 The device may serve to support packages of merchandise of various characters, display cards, other supports, and the like. Advertising matter may be printed upon the faces of the device if desired.

10 The devices may be shipped or transported flat, as shown at Fig. 1, or the same may be folded accordion-like along the lines 11, 12 and 13, to dispose the lateral portions 14 one over the other with the portions 15 between 15 the same, and thereby providing a very compact article which may be packed with the goods to be displayed, or packed for shipment or storage.

It is to be noted that while I have shown 20 the supporting device constructed to receive and retain an article of rectangular or box-like form, that the recesses or notches provided in the upper edges of the intermediate portions may be varied to receive and 25 support articles of different shapes or contours.

Having thus described my said invention, what I claim and desire to secure by Letters Patent is:

30 1. A device of the character described comprising a blank having a straight lower edge foldable along three defined vertical lines to provide outer portions and intermediate portions; said intermediate portions 35 being of reduced height relative to said outer portions and, when said blank is adjusted to operative position, converging forwardly from said outer portions to form a V-shaped support having upper edges extending forwardly and downwardly from intermediate points on said outer portions and providing recesses adapted to receive an article to be displayed; said outer portions projecting laterally at the rear of said 40 intermediate portions transversely of said upper edges to form angles with said intermediate portions, substantially as specified.

45 2. A device of the character described comprising a blank having a straight lower edge foldable along three defined vertical

lines to provide outer portions and intermediate portions; said intermediate portions being of reduced height relative to said outer portions and, when said blank is adjusted to operative position, converging 55 forwardly from said outer portions to form a V-shaped support having upper edges extending forwardly and downwardly from intermediate points on said outer portions and providing recesses adapted to receive 60 an article to be displayed; said outer portions projecting laterally at the rear of said intermediate portions transversely of said upper edges to form angles with said intermediate portions, and means engaging the 65 upper edges of said outer portions adjacent to the inner edges thereof whereby to hold the device to adjusted position with said outer portions in spaced relation to each other, substantially as specified. 70

3. A device of the character described comprising a blank having a straight lower edge foldable along three defined vertical lines to provide outer portions and intermediate portions, said outer portions having recesses in the upper portions thereof adjacent to their inner edges; said intermediate portions being of reduced height relative to said outer portions and, when said blank is adjusted to operative position, converging forwardly from said outer portions to form a V-shaped support having upper edges extending forwardly and downwardly from intermediate points on said outer portions and providing recesses adapted to receive an article to be displayed; said outer portions projecting laterally at the rear of said intermediate portions transversely of said upper edges to form angles with said intermediate portions, and an elastic member having opposite ends secured within the recesses in said outer portions whereby to hold the device to adjusted position with said outer portion in spaced relation to each other, substantially as specified. 75

Signed at the city of New York, borough of Manhattan, in the county and State of New York, this 28th day of January, one thousand nine hundred and twenty-six.

THOMAS H. WILKINSON.
